UNITED STATES PATENT OFFICE.

GEORGE B. BOSCO, OF CHICAGO, ILLINOIS.

FORM CLAMP.

Application filed December 3, 1921. Serial No. 519,692.

To all whom it may concern:

Be it known that I, GEORGE B. Bosco, a citizen of the United States of America, and a resident of Chicago, county of Cook, 5 and State of Illinois, have invented a new and useful Improvement in Form Clamps, of which the following is a specification.

This invention relates to form clamps particularly designed for holding together 10 the separable parts of a concrete mold such as those which are used in building concrete columns, joists and girders.

The main objects of this invention are to provide a form clamp which is simple, inexpensive and effective, and having an improved form and arrangement of interlocking parts; to provide improved means for adjusting the parts to accommodate different sizes of molds; and to provide a detachable 20 tool for drawing the interlocking parts toward each other to tighten the clamp.

An illustrative embodiment of this invention is shown in the accompanying drawings, wherein—

25 Figure 1 is a perspective view of a column mold, partly broken away, and having applied thereto a form clamp embodying this invention.

Figure 2 is a longitudinal vertical section of the interlocking members of the clamp.

Figure 3 is a plan of the interlocking members.

Figure 4 is a side elevation of the complete clamp and detachable tool, the flexible band being shown partly broken away.

The majority of form clamps which are now in use comprises a plurality of similarly formed sections having means for adjustment at each corner of the mold. Such clamps cannot properly be applied to a column mold without the services of two men, because the clamp sections should be interlocked simultaneously on opposite sides 45 of the mold in order to prevent the form from being distorted.

The present clamp comprises a single flexible metallic band having adjustably secured thereto a pair of members formed for 50 interlocking engagement for securing the band around the form. The interlocking members are drawn together into locking position by a separate tool which is detachable so that one such tool may serve a large 55 number of clamps.

Referring to the drawings, the clamp is

shown applied to a concrete column mold comprising side sections which are formed of planks 1, secured together by battens 2 arranged on the outside of the mold at certain intervals and disposed transversely to the planks. 60

In the form shown, the clamp comprises a flexible element 3, adapted to embrace the mold and having its ends secured to interfitting members 4 and 5 arranged for telescopic engagement, and which are drawn into interlocking relation by a detachable tool 6. 65

The flexible element preferably comprises 70 a flat strap of metal, of sufficient width to insure a proper grip of the interlocking members.

The members 4 and 5 are preferably each in the form of a metal casting comprising 75 a head 7 and a shank 8. The head 7 includes a pair of flanges 7.1 arranged in substantially parallel spaced relation and extending beyond one end of the shank for supporting a pair of transversely disposed 80 pins 9 and 10, which are spaced apart with respect to each other and the adjacent end of the shank 8 so as to permit the ends of the metal strap to be laced around the pins as shown in Fig. 1, for securing the strap 85 against slipping by the friction of the overlapping parts. This form of lacing permits the interfitting members to grip the flexible strap at any point along its length and the clamp is, therefore, adjustable to 90 accommodate molds of various sizes. The pins 9 and 10 may be separately formed and inserted through suitable apertures in the flanges 7.1, but in the drawings the pins are shown as preferably cast integral with the 95 interlocking members. The pin 10 is provided with a flat or preferably slightly concave face on the purchase side 11 thereof, so as to form a pair of shoulders 12 for putting a kink in the metal strap and thereby increasing the friction between the strap and 100 interlocking members.

Projecting outwardly from the flanges 7.1 in alinement with the pin 10, is a pair of oppositely disposed lugs 13, arranged for engagement with the tool 6, for drawing the interlocking members into position to permit their being interlocked. 105

The member 4, or male part of the clamp, has its shank extended to form a tongue 14, 110 and the member 5, or female part of the clamp, has an enlargement 15 formed at the

outer end of its shank and provided with a slot or socket 16 for receiving the tongue 14. Extending through the members 4 and 5, is a plurality of apertures 17 arranged to receive a locking pin 18 and disposed so as to permit the interlocking of the parts in various relative positions. The locking pin is preferably in the form of a nail which may be driven into the batten of the mold.

10 The detachable tool 6 comprises a slide bar 19, having mounted thereon a stationary jaw 20, and a movable jaw 21, which are both formed with claws 22, for engagement with the lugs 13 of the interfitting parts 4 and 5.

15 The bar 19 is preferably made of steel and the jaws are preferably made of cast metal and are formed with centrally located openings to receive the slide bar. The stationary jaw 20 is fastened to the bar 19 by a pin 23, 20 which permits a slight rocking movement of the stationary jaw so as to permit the jaw to be rocked into frictional engagement with the upper and lower edges of the bar 19, thereby relieving the pin 23 of all strain.

25 The movable jaw 21 is actuated by a hand screw 24, which is carried by a head 25 mounted on the adjacent end of the bar 19. One end of the screw 24 engages a socket (not shown) formed in the jaw 21 and the 30 other end of the screw is provided with a crank handle 26.

In operation, the clamp is applied to a column mold with the flexible strap embracing the battens 2 as shown in Fig. 1, any appreciable slack in the strap having first been taken up by adjusting the lacing. The tool 6 is then applied to the members 4 and 5 with the claws engaging the lugs 13. By operating the hand screw 24 the strap is 40 tightened by drawing the interfitting members into position to permit the insertion of the pin 18 through certain of the aligned apertures. When the locking pin has been inserted through the apertures and driven 45 into the mold, the detachable tool may be removed and used on other clamps.

When the clamp is used on a circular form, suitable filler blocks (not shown) may be inserted between the interlocking members 50 and the mold.

It is apparent from the foregoing description that the present invention provides a simple and effective column clamp in which there are no projecting parts and which can 55 be readily applied to a mold by one person.

Although but one specific embodiment of this invention is herein shown and described, it will be understood that numerous details of the construction shown may be altered or 60 omitted without departing from the spirit of this invention as defined by the following claims.

I claim:

65 1. A form clamp comprising a flexible element adapted to embrace the form, a pair

of members on said element formed for interfitting engagement, a detachable tool for drawing said members into interfitting engagement to permit the interlocking of said members, said tool comprising a body having a pair of jaws adapted for engagement with said members, and a screw mounted on said body and arranged for moving one of said jaws relatively to the other jaw.

2. A form clamp comprising a flexible element adapted to embrace the form, a pair of members on said element formed for interfitting engagement, a detachable tool for drawing said members into interfitting engagement to permit the interlocking of said members, said tool comprising a bar having a pair of jaws mounted thereon for engagement with said members, one of said jaws being fixed on said bar, the other of said jaws being slidable along said bar, and a screw mounted on said bar and arranged to move said other jaw along said bar relatively of said fixed jaw.

3. A clamp of the class described comprising a pair of relatively slidable members adapted for interlocking engagement, and a flexible band connecting said members, one of said members having a pair of transversely disposed pins arranged in spaced relation, one end of said band being bent around one of said pins and laced through the space between said pins whereby said band is adjustably secured to said one member by the friction of the overlapping parts of said band at the lacing.

4. A clamp of the class described comprising a pair of relatively slidable members adapted for interfitting engagement, each of said members having a pair of transversely disposed pins arranged in spaced relation, a flexible band connecting said members, the ends of said band being bent around certain of said pins and laced through the space between the pins of each pair whereby said members are adjustably secured to said band by the friction of the overlapping parts of said band at the lacing, and a detachable tool for drawing said members into interfitting engagement to permit the interlocking of said members.

5. A clamp of the class described comprising a pair of relatively movable members adapted for interlocking engagement, a flexible band connecting said members, each of said members comprising a shank having a head extending beyond one end of said shank, and a pair of transversely disposed pins mounted on said head and arranged in spaced relation with respect to each other and to said shank, the ends of said band being laced through the space between said pins and shank and doubled back upon said band at the lacings.

6. A clamp of the class described comprising a pair of relatively movable mem-

bers adapted for interlocking engagement, a flexible band connecting said members, each of said members comprising a shank having a pair of spaced flanges projecting beyond one end of said shank, a pair of transversely disposed pins extending between said flanges in spaced relation to each other and to said one end of the shank, a pair of oppositely disposed lugs extending outwardly from said flanges, the ends of said bands being laced through the spaces between said pins and the shank and doubled back upon said band at the lacings, and a detachable tool adapted for engagement with said lugs for drawing said members into position to permit the interlocking of said members.

7. A clamp of the class described comprising a pair of relatively movable mem-

bers adapted for interlocking engagement, a flexible band connecting said members, each of said members comprising a shank having a head extending beyond one end of said shank, and a pair of transversely disposed pins mounted on said head and arranged in spaced relation with respect to each other and to said shank, the ends of said band being laced through the space between said pins and shank and doubled back upon said band at the lacings, the shank of one of said members being formed to provide a socket for receiving the shank of the other of said members, said shanks having apertures for receiving a locking pin.

Signed at Chicago this 30 day of Nov. 35 1921.

GEORGE B. BOSCO.
